HENRY R. LILLICH AND CARTER SMITH, OF BORING, OREGON

UMBRELLA

Application filed August 10, 1928. Serial No. 298,723.

Our invention relates to umbrellas, and an object thereof is to provide a collapsible umbrella which may be readily collapsed so that it can be carried in a hand bag or pocket of the user.

5 Further, the invention provides a collapsible umbrella wherein the pivoted ribs are securely held against movement when the umbrella is not in use.

10 With the preceding and other objects and advantages in mind, the invention consists in the novel combination of elements, construction and arrangement of parts to be hereininafter specifically referred to, claimed and 15 illustrated in the accompanying drawings, wherein:

Figure 1 is a longitudinal sectional view illustrating the umbrella in partially raised position.

20 Figures 2 and 3 are perspectives of the umbrella rib sections.

Figure 4 is a transverse sectional view taken on line 7—7 of Figure 1, and

25 Figure 5 is a similar view taken on line 5—5 of Figure 1.

Referring to the invention in detail, a collapsible handle is provided comprising an intermediate tube 5 and end tubes 6 and 7 which are slidably received on the intermediate tube. As illustrated in Figure 1, the opposite ends of the intermediate tube are formed with circumferentially spaced longitudinally extending resilient fingers 8 adapted to frictionally engage the walls of the 30 tubes 6 and 7 to retain these sections in adjusted position. To prevent the tubes 6 and 7 from moving beyond the ends of the tube 5, the inner ends of the tubes 6 and 7 are restricted or of decreased diameter as indicated at 9.

40 For the purpose of preventing the tubes 6 and 7 from rotating on the intermediate tube 5, the latter is provided with diametrically opposed slots 10 for substantially its entire 45 length and which receive laterally projecting lugs 11 projecting from the inner faces of the tubes 6 and 7.

Spaced about the handle and normally extending parallel thereto is a plurality of ribs 50 12. Each of these ribs comprises a channel

spaced rib section 13 having its forward end closed and terminating in an ear 14 which is pivoted to the upper end of the tube 7 by a pivot pin 15. A slidable rib section 16 is longitudinally adjustable in the rib section 55 13 and carries a laterally extending ear 17 at its upper end which is adapted to engage at stop 18 formed with the extremities of a U-shaped member 19 on the lower end of the rib section 13 when the rib section 16 is in extended position. The legs of the U-shaped member and the stop 18 is provided with a continuous groove 20 for the reception of thread employed to sew the umbrella covering (not shown) to the lower end of the rib 60 section 13. A tip 21 is carried by the lower end of the slidable rib section. The tip 21 is provided with a resilient longitudinal extension 21^a which normally extends along the outer face of the slidable rib section. At 65 its free end, the extension 21^a is bevelled as at 22^a whereby the extension is caused to slide over the outer face of the rib section 13 to cause the umbrella covering (not shown) to fold when the umbrella is being collapsed. 70

In order to hold the rib sections against lateral separation, a rod 22 extending longitudinally within the slidable rib section has its upper end bent around the pivot 15 as at 23 while its lower end terminates in a right 75 angular extension 24 which projects beneath the stop 18. It will be observed that the slidable rib section is free to slide within the rib section 13 or extended therefrom when the 80 umbrella is to be used.

A collar 25 is slidable longitudinally on the handle and carries a plurality of laterally disposed pivoted braces 26, each of which has its upper end pivoted to the lateral ear 17 of one of the ribs. A conventional resilient 85 latch 27 is carried by the upper end tube 7 for engagement with the collar to retain it in elevated position when the umbrella is raised. A similar latch 27^a is carried by the end tube 6 for engagement with the collar when the 90 umbrella is in collapsed position.

To retain the ribs parallel to the handle when the umbrella is collapsed, a hand grip 28 is carried by the lower end of the tube 6 and is provided with a circular recess 29 in its 100

upper end for the reception of the rib tips as illustrated in Figure 3. An elastic ring 30 is arranged within the recess 29 for contact with the tips when in this position.

5 With the umbrella in collapsed position as illustrated in Figure 1, it is arranged in the open position by sliding the tubes 6 and 7 away from each other on the intermediate tube 5. By reason of the collar 25 being 10 latched on the tube 6 and the rib sections 13 being movable with the tube 7, the slideable sections of the ribs will be extended. The collar 25 is now elevated and latched to retain the umbrella in open position. When 15 it is desired to collapse the umbrella, the collar is first slid downwardly and latched on the tube 6. Pressure now exerted on the opposite ends of the tubes 6 and 7 will move the same toward each other and at the same time 20 slide the slideable rib sections into their corresponding sections 13.

What is claimed is:

An umbrella rib including a pair of channel shaped members, one of which is slidably 25 received in the other, and a rod extending longitudinally within one of the channel shaped members and lying within the other of such channel shaped members when collapsed to prevent lateral separation of the 30 channel shaped members when so collapsed.
